ABSTRACT

There is disclosed herein equipment for a game including a divining rod device, gameboard and playing cards. The divining rod device includes a handle member having pivotally attached thereto a counterbalanced arm or rod with a magnet at one end thereof. The gameboard is of laminated construction and has a metal inner layer. The playing cards have various indicia thereon and are positioned at indicated locations on the gameboard. The divining rod device is held by the handle member substantially parallel with the board and several inches thereabove. The end of the rod with the magnet is in the form of a pointer which is swept back and forth over the board until this end makes contact with a card on the board because of the attraction of the magnet to the board. In this manner, a card is selected to thereby provide a "reading" according to the game.

MAGNETIC DIVINING ROD GAME EQUIPMENT

This invention relates to games and the like and more particularly to divining rod equipment utilizing the principals of magnetic attraction for providing a new game.

The present game combines the age-old mysteries of the divining rod and the lodestone to provide interesting answers or results, which are called herein "psychomagnetic" results or readings. As a background, it should first be mentioned that in the past there were two very closely related ancient forms of divination. The first was Belomancy in which an arrow was tossed in the air so that a person could start in the direction toward which it finally pointed, and the second was Rhabdomancy, where a wand served a similar purpose but was retained lightly in the grasp of the operator thereby allowing the wand to waiver until it settled on a course.

According to history, these devices became more than just primitive directional finders. They were used to indicate and object, pick out a person from a group, and answer questions by pointing one way for "yes" and another for "no." Rhabdomancy, in particular, lent itself to further development by the "wise" men of their day, whose wands could designate scrolls on which names had been written. The wand came to be recognized as a symbol of magical authority, a distinction that it held up until modern times.

Meanwhile, however, the earlier practitioners of this type of divination, the Chaldeans and the Persians, had carried it into Scythia, the region north of the Black Sea; and from there, it eventually reached some of the Germanic tribes. They frequently practiced it in crude form, simply using twigs or small branches from trees, casting them on the ground, or gripping them, whichever suited the particular purpose or occasion.

Along with the divining rod was another ancient discovery that was popularly associated with it, though one belonged in the mental realm and the other was purely physical. That other marvel was the lodestone, a peculiar type of mineral rock which had the power of attracting iron. For centuries this phenomenon was attributed to a magical or supernatural force, and with the invention of mariner's compass toward the 13th century A.D. the superstition increased. Since the compass constantly pointed north, people imagined that there must be a huge mountain of magnetic iron somewhere in that icy realm, powerful enough to draw the nails from an approaching ship and thereby wreck it.

Such beliefs forged a stronger link between the compass and the divining rod, particularly in mining areas. Only iron drew the compass needle from the true north, but it seemed logical that other metals might give off invisible emanations akin to magnetism that could be picked up by the divining rod. It was put to the test in the Hartz Mountains of Germany as early as the year 1430 using the primitive rods cut from tree branches, and soon it became an accepted method of locating sites for new mines.

While various types of rods were used, including both straight and curved, the most popular form was a forked tree branch that enabled the operator to grip both ends and extend the main portion forward so that it would dip when attracted by the underground metal. According to contemporary accounts, this form of divination was successful and it was later brought to England by German miners who were hired to develop new mines in Cornwall and Wales. There, the results were reportedly quite satisfactory and the only reason that it was finally abandoned was because after many years, the mines were worked out and there was no use bothering with them any longer.

Meanwhile, in France, diviners had been using forked rods to locate lost objects and trace missing persons, but that also proved to be a limited field. As with all new discoveries and inventions that have proven their worth, the trend was to put the divining rod to the greatest possible use and that proved to be the search for water, the universal element which all humanity needs. Again, success greeted the diviners and "water-witching" as it came to be known, spread rapidly through Europe and America, and today, after several centuries, it is still practiced.

Another theory offered to explain dowsing, as water-witching is more correctly termed, is that the dowser, while walking above an underground stream, subconsciously picks up a slight vibration and responds with an instinctive muscular action that causes the rod to dip. If true, this is no more remarkable than the fact that a scientific instrument called the seismograph can register tremors from an earthquake thousands of miles away. But something more than vibration is obviously involved when modern dowlers apparently find water by running a divining rod above a large-scale map, instead of the actual ground.

All this has produced further theories involving cosmic rays or occult forces, which in turn can be linked with astrological lore and planetary influences, while modern experimenters with the divining rod have attributed its operation to extrasensory perception, thus merging the old with the new.

With this background in mind, be it true or folklore, the present concepts may be generally described as a new combination of the age-old ideas of Rhabdomancy and the lodestone to provide a new and novel game for producing "psychomagnetic" results. The present game equipment includes a magnetic divining rod device having handles and a balanced rod pivotally supported thereby. A pointer end of the rod includes a magnet, and with the rod pivotally hung and balanced from the handles, it is sensitive to the slightest subconscious impulse. A gameboard is provided having a metal innerlayer to which the magnet is attracted when the pointer end is moved sufficiently close to the board. With certain indicia on the board, either printed thereon or in the form of charts or cards, the attraction of the pointer to any particular indicia provides what may be termed a "psychomagnetic" reading or answer.

Accordingly, it is a principal object of the present invention to provide new game equipment.

It is an additional object of this invention to provide a new game including a pivotally mounted rod and a gameboard which are mutually magnetically attracted together.

A further object of this invention is to provide new game equipment including a gameboard having a metal innerlayer, indicia which may be in the form of playing cards positioned on the board, and a magnetic divining rod device including a handle member and a rod with a magnet affixed thereto, the rod being pivotally attached to the handle member.

It is another object of this invention to provide a novel magnetic divining rod device.

These and other objects and features of the present invention will become better understood through a consideration of the following description taken in conjunction with the drawings in which:

FIG. 1 is a perspective view of the present magnetic divining rod device;

FIG. 2 is a top view of the device of FIG. 1;

FIG. 3A is a cross-sectional view of the rod and support bracket of the device of FIGS. 1 and 2;

Briefly, there is disclosed herein a new game and suitable equipment used in playing the game. The equipment includes a magnet divining rod device comprising a handle member having pivoted thereunder an elongated rod which is weighted at one end and has a magnet affixed to the other end thereof, the latter end serving as the pointer end of the rod. The rod is attached to a support bracket, and is adjustable with respect to lancing the rod, and the bracket is pivotally connected to the underside of the handle member. The handle is of any suitable size and form and have at least one portion to which the magnet of the pointer is attached.

An exemplary board is of laminated construction of thin steel sheet laminated between paper. The playing cards have various indicia which may be circular and cut from suitable paper.

the drawings, FIG. 1 is a perspective view of a divining rod device. This device includes a generally designated 10 which is composed of two generally designated 11 and 12 jointed to a central support section 13. The sections 11-13 may be formed of any suitable material, and typically is molded of polypropylene, in any desired form and shape. A wire brad 14 is provided in each of a pair of apertures in the underside of the support section 13. A support bracket 15 is hung from the brad 14 and is generally designated 16. The bracket 15 has an aperture 17 through which the brad 14 extends, thereby supporting or hanging the support 15 from the support section 13. The interior edge of the aperture 17 is curved, as best seen in FIG. 3B, to provide a minimum clearance with the brad 14.

may be a cylindrical rod portion 19 having a forward end thereof and a counterbalance 21 at thereof. The pointer 20 has a magnet 22 at, and the counterbalance 21 has a weight 23 at. The entire rod 16 may be molded from magnet 22 and weight 23 may be heat sealed at ends of the rod. The pointer 20 of the rod is at degrees, for example ten degrees, from the longitudinal axis of the rod as best seen in FIG. 3A. This offset device to be tilted downward slightly while the magnet 22 substantially parallel with the playing the game as will be explained sub-tion 19 includes an intermediate rectangular V-grooves 26 on the upper part thereof, mate with similar V-grooves 27 in the lower he support bracket 15. board 30 with which the magnetic divining rod is illustrated in FIGS. 4A and 4B. The board 30 is in the form of a typical gameboard and may be in the middle as indicated by dashed lines 31, but a laminated construction inasmuch as the board on its surface or within its construction a suitable such the magnet 22 is attracted. An exemplary structure is illustrated in FIG. 4B and includes (a) a layer of paper 32 such as lithograph label stock, (b) a 10-pound book stock 33, 2-mil steel 34, and 50-stock 35, (c) a layer 36 of chipboard, such as 21-board, and finally (d) a back wrapper 37. The various layers may be secured together with any suitable adhesive. The board is 19 $\frac{1}{2}$ inches square with two pieces of 34b as indicated in FIG. 4A, each slightly smaller than half to provide a 3/16-inch margin all around the steel. With this size board, the length of the rod is 3 $\frac{1}{2}$ inches. A suitable magnet may be 11/16 inch wide and high.

40-48 around the upper part of the "sun" 49 and the lower "Planetary," "Divination," "Fate," "Zodiac," and "Numerology" circles 50-54 at the bottom of the board. The lower four circles 56-59 indicate the original sections where the playing cards (FIGS. 5-8) normally are stacked.

10 Although it will be appreciated that any suitable indicia may be provided on the board in any suitable manner, such as printing directly thereon, separate charts, separate cards, and so forth, individual playing cards as illustrated in FIGS. 5 through 8 are preferred. Each of these cards has various indicia printed thereon to provide a "reading" in producing the "psychomagnetic" results mentioned earlier. FIG. 5 illustrates suitable Planetary cards, FIG. 6 illustrates suitable Zodiac cards, FIG. 7 illustrates suitable Numerology cards, and FIG. 8 illustrates suitable Divination cards. Each card may be die-cut to a circle having a diameter of $2\frac{1}{4}$ inches from three-ply paper stock. The indicia and suitable colors may be imprinted thereon. For example, one side of the cards are imprinted as illustrated in FIGS. 5 through 8, and the backs of these cards 15
20 may be labeled "Planetary," "Zodiac," "Numerology," and "Divination."

In playing a game with the present magnetic divining rod equipment, certain cards are placed on the gameboard 30.

25 The handles 11 and 12 of the divining rod device 10 are held with both hands of the operator and with the pointer 20 facing away from the operator. The pointer 20 should be about 4 inches above the gameboard and substantially parallel thereto with the pointer 20 floating above the cards. The divining rod device 10 is then moved slowly over the entire set of cards from one end to the other while lowering it gradually, but without conscious control, until it dips sufficiently far that it is drawn to one card. The indicia on the face of this card then provides certain information depending upon which aspect of the present game is being conducted. Set forth below are suitable and exemplary rules which may be used in playing the present game.

The rod 16 is adjusted with respect to the bracket 15 as noted earlier so that the pointer 20 tips down slightly. Each set of cards illustrated in respective FIGS. 5 through 8 is shuffled and placed face down on the four lower circles 56-59 at the bottom of the gameboard 30. Different types of readings can be made. For a full reading, the Planetary cards illustrated in FIG. 5 are placed face down on the nine circles 40-48 around the sun 49 at the top of the gameboard 30. It is not necessary to place the cards down in any particular order, and the 10th card is placed face down in the Fate circle 52 below the sun. The rod device 10 is held above the board with the pointer 20 approximately 4 inches above the board as noted earlier. It is moved slowly over the entire line of nine circles 40-48 above the sun from one end to the other, and is lowered gradually until it dips down onto one card. The designated card is turned up and placed face up in the Planetary circle 50. The other Planetary cards are removed from the upper circles 40-48 and replaced in their original section 56 at the bottom of the board, with the exception of the card in the Fate circle 52 which remains through the next stage of the game. The selected Planetary card which is now face up on the Planetary circle 50 indicated the subject best suited for continued divination. A question is mentally selected pertaining to the subject on the face up Planetary card. For example, with the card Venus-Love and Romance, the question may be, "Is love coming my way now?".

The Divination cards on the circles 57 are now used in finding an answer to the above question. The nine Divination cards illustrated in FIG. 8 are placed face down on the nine circles 40-48 around the sun in any order. Again, the rod 16 is moved over the layout until drawn down to one of the cards. The selected card is turned face up and if it indicates Yes, No, Favorable, or Doubtful, it is placed on the Divination circle 51 on the gameboard. The other Divination cards are removed and replaced in their section 57 at the bottom of the gameboard.

If the selected card indicates Not Concentrating, the Divination cards are gathered up, mixed and replaced at 57, using the rod for another try. If the card that turns up indicates Fate, the card now in the Planetary circle 50 is removed and put back with the others at 56, and the card in the Fate circle 52 is turned up and transferred to the Planetary circle 50 instead. Since this provides a new subject, all the Divination cards are gathered, mixed, and replaced at 57 while concentrating on a new question.

As an example of a change of this nature, if the Planetary card from the Fate circle should be Neptune-Travel, the question, "Is love coming my way now?" might be changed to, "Am I going to take a trip?" Again, the rod is used to obtain a "psychomagnetic" answer.

Whatever the answer from the Divination cards, the Zodiac cards can then be used to determine the time of its fulfillment. The nine Zodiac cards are placed at random in the upper circles 40-48 and the other three are stacked in the Fate circle 52, all face down. The rod is used again to find a card which, when turned up, will indicate the period in which to expect results, good or bad. This card is placed in the Zodiac circle 53.

Assuming that the question, "Is love coming my way?" was answered by a Yes card, the Zodiac card is used to tell when. If No is the answer, one mentally asks, "When should I ask this question again?" or "How long will I have to wait?" If the Divination card said Favorable, the Zodiac card indicates a period which is most ardent in the purpose. If Doubtful, it indicated the period when caution is to be used.

As an alternate example, assume the question came from the Neptune-Travel card and was worded, "Am I going to take a trip?" and if the Divination card should indicate Yes, the Zodiac card indicates the probable period. If the Divination card should be No, it would signify not at that period, or that a trip should be avoided at this time. With Favorable, that could be the time to take the trip if possible; with Doubtful, a disappointment or postponement is indicated.

If the period stated on the Zodiac card is just past, almost gone, or in any way doubtful, the top card in the Fate circle 52 can be turned up to obtain an alternative answer. In fact, turning up that card is a good policy, as it may suggest a time for action, or inaction, as the case may be.

For a final test, the Zodiac cards are removed from the upper circles 40-48, replaced in their section 58, and the Numerology cards are used to determine a specific day which may be favorable or which should be avoided. To do this, the Numerology cards numbered from 1 to 7 are mixed and placed face down on the upper circles 41-47, leaving the end circles open. The rod is passed over the seven-card layout. The card selected indicates the day of the week, counting the days of the week as 1 for Sunday, through to 7 for Saturday, on which results may occur.

In all "full" readings as described above, there are four regular steps, utilizing the Planetary cards, Divination cards, Zodiac cards and Numerology cards, in that order. Even if a question is answered by No on a Divination card, the reading can be continued, because the Zodiac and Numerology cards tell the period and day of negative results or disappointment.

However, with more specialized questions, there is no reason to continue if a Divination card comes up with No as an answer. For example: in its first run, the rod settles on the Planetary card for Mercury, which signifies Luck or Chance. The question "Should I invest in a new industrial plant?" is asked, and the Divination cards are placed around the sun. If the rod brings up the answer "No," that is it, and it is no use trying to find out when not to invest. The subject should be dropped and proceed on to some other question, or another person should have a try.

As the questions become still more specialized, the routine can be altered further to suit the case. That in itself provides intriguing situations which produce more fun.

Special readings and their treatment are discussed below.

1. The Planetary cards are dealt to the circles 40-48 and the rod settles on Venus-Love and Romance. The individual puts the mental question: "Am I going to have a new romance?" The Divination cards are dealt and the answer comes up Yes. (If No, the question would be dropped; but with Favorable or Doubtful, it can be carried further, as with Yes.)

Now, the individual makes a list of persons who might figure in the new romance, numbering them, as: 1-Janie, 2-Mary, 3-Kay, 4-Helen, 5-Candy, and 6-Mystery. The sixth "mystery" should be included in case the individual is uncertain about most of the others. In any case, the Numerology cards are now utilized, from 1 to 6 (or 1 to 5, if the mystery is not included). Again, the rod is called into play to pick the future object of the individual's affection.

2. The Planetary cards are dealt and the rod settles on Mercury-Luck and Chance. Assume that it so happens that the individual is thinking of going to the races tomorrow. He places the Divination cards and asks: "Should I go to the races tomorrow?" If he goes to the races regularly, that would be unnecessary, but if there is any doubt, he should ask this question. Assume that the rod responds Yes. Again, the individual mixes and places those same cards and asks "Have I any chance of winning?" If the answer is Yes, Favorable, or even Doubtful, he can continue. But assuming that the answer is on the positive or possible side, then he deals out the Numerology cards, asking the question, "Which is the best race?" If it comes up "3," he uses the same cards again, asking, "Which is the best horse in the race?" If it comes up "6," this indicates Number 6 in the third race.

3. The Planetary cards are dealt and the rod settles on Jupiter-Wealth and Ambition. Assume that the individual has three prospective business partners, who might help gain these aims. The Divination cards are dealt out, and an example question is, "Can I succeed in my coming deal?" The rod then settles on Yes or Favorable. The problem now, is which partner. They can be numbered and the Numerology cards used, but their birth signs can be used if their birthdays are known and are at different times of the year. One may be called Mr. Taurus, another Mr. Scorpio, the third, Mr. Libra, and the three Zodiac cards bearing those signs are laid out. Again, the rod is used to see what turns up.

4. Assuming that a girl about to be married turns up a card saying Venus-Love and Romance, her next question might be: "Will I have any children?" That calls for the Divination cards and if the rod settles on Yes, or Favorable, the next question could be: "How many?" That would mean mixing the Numerology cards from 1 to 7 and running along the entire row.

The present game also includes three ways of "testing" the powers of the inner mind through the "psychomagnetic" attraction of the rod, all following the pattern of experiments which have been conducted in parapsychology laboratories at various college.

5. The first is a "clairvoyance test." Literally interpreted as "clear seeing," this represents the psychic faculty of gaining an image or impression of an unseen object. To test this function, two or more cards of one set are mixed and placed face down on the circles of the board. The rod is used as described above to pick on card "psychomagnetically." If the individual has clairvoyant power, this seemingly random choice will be guided to the card that represents the subject to answer that is subconsciously sought.

6. The next is the "precognition test." In this case, the cards are dealt face up, so that the individual is aware of each subject, or all possible answers. The procedure is the same, but in using the rod, a mood of complete impartiality is maintained so that apparently the rod alone picks out the card that represents the probable future event. If there is a precognitive power, the inner knowledge is the guiding force.

7. The third is the "telepathic test." Worked with cards either face up or telepathic down. Other people concentrate upon one of the cards, noting it by name or number if face up; while with face down cards, they merely choose a card according to its position in the row. The individual or consultant runs the rod back and forth in the usual fashion until it settles upon a card. One lucky hit does not necessarily indicate a telepathic ability of picking up other people's thoughts, but repeated successes that run well above the law of average may be significant.

The "telepathic test" may be worked two ways. (1) In the presence of the people who are concentrating on the card; they deal them while the individual working the rod is out of the room. The individual returns and proceeds to use the rod. (2) With the people absent, thus making it a case of "remote telepathic control." They deal the cards while the individual is out; then they come from the room and the individual goes in, calling for them to return after the rod scores its hit. Either way, turns may be taken by different people, each acting as the telepathists, to see which member of the group can run up the biggest score of successful hits.

Other questions and uses for the present game equipment will be apparent. It should be appreciated that the foregoing are exemplary rules for the present game which is for the purpose of providing fun and enjoyment.

The present embodiment of this invention is to be considered in all respects as illustrative and not restrictive, the scope of the invention being indicated by the appended claims rather than by the foregoing description and all changes which come within the meaning and range of equivalency of the claims are therefore intended to be embraced thereby.

What is claimed is:

1. A divining rod type game comprising magnetic divining rod means including a handle member by which an operator may hold said divining rod means, and including a rod having an end with a magnet affixed thereto, said rod being pivotally attached to said handle member about an axis transverse to its length in a balanced relationship which can be upset by magnetic attraction between said magnet and proximate ferromagnetic material, and a gameboard with which said divining rod means is used and to which said magnet is attracted as said rod is passed over said gameboard, said gameboard including a laminated construction having at least a section of material to which said magnet is attracted and having indicia thereon for providing a "reading" when said magnet becomes sufficiently proximate to said gameboard to upset said balanced relationship, and pivots to said gameboard.

2. A game as in claim 1 wherein said gameboard comprises an upper layer of material and a lower layer of material, and said material section is intermediate said layers of material.

3. A game as in claim 1 wherein said indicia on said gameboard comprise a plurality of playing cards positioned thereon, each of said playing cards having predetermined indicia printed thereon.

4. A divining rod type game comprising magnetic divining rod means including a handle member by which an operator may hold said divining rod means, and a rod pivotally attached to said handle member, said handle member including a pair of arcuate handles jointed together by a central section and a hood member secured to the underside of said central section, said rod including an elongated member having a first end forming a pointer with a magnet affixed thereto and a second end serving as a counterbalance, and bracket means pivotally coupled with said hook member and secured to said rod intermediate the ends thereof, and

a gameboard with which said divining rod means is used and to which said magnet is attracted as said rod is passed over said gameboard, said gameboard including a laminated construction comprising an upper layer of material and a lower layer of material and a metal section intermediate said layers of material, and said gameboard having indicia thereon.

5. A divining rod type game comprising magnetic divining rod means including a handle member by which an operator may hold said divining rod means, and a rod pivotally attached to said handle member, said rod having an end with a magnet affixed thereto and a second end which is weighted to balance said rod in a depending relationship from said handle member, and a gameboard with which said divining rod means is used and to which said magnet is attracted as said rod is passed over said gameboard, said gameboard including a laminated construction having at least a section of metal to which said magnet is attracted and having indicia thereon for providing a "reading" when said magnet is attracted to said gameboard.

6. A divining rod type game comprising magnetic divining rod means including a handle member by which an operator may hold said divining rod means, said handle member comprising a pair of handles jointed together by a central section, and a hook member secured to the underside of said central section, and a rod pivotally attached to said handle member, said rod comprising an elongated member including first end forming a pointer and a second end serving as a counterbalance, said first end having a magnet affixed thereto, and bracket means pivotally coupled with said hook member and secured to said rod intermediate the ends thereof, and a gameboard with which said divining rod means is used and to which said magnet is attracted and having indicia thereon for providing a "reading" when said magnet is attracted to said gameboard.

7. A divining type game comprising magnetic divining rod means including a handle member by which an operator may hold said divining rod means, said handle member comprising a pair of handles jointed together by a central section, and a hook member secured to the underside of said central section, and a rod pivotally attached to said handle member, said rod comprising an elongated member including a first end forming a pointer and a second end serving as a counterbalance, said first end having a magnet affixed thereto, and said second end being weighted to balance said rod in a depending relationship from said handle member, and a gameboard with which said divining rod means is used and to which said magnet is attracted as said rod is passed over said gameboard, said gameboard including a laminated construction having at least a section of metal to which said magnet is attracted and having indicia thereon for providing a "reading" when said magnet is attracted to said gameboard.
